CURRENT-CONTROL APPARATUS

Charles P. West, Pittsburgh, Pa., assignor to
Westinghouse Electric & Manufacturing Company,
East Pittsburgh, Pa., a corporation of
Pennsylvania

Application November 25, 1932, Serial No. 644,285

11 Claims. (Cl. 171—312)

My invention relates, generally, to current-control apparatus and, more particularly, to apparatus for controlling the current in a plurality of electrical circuits in a predetermined manner.

5 While not limited thereto, my invention is particularly applicable to the control of flood-lighting circuits or for general interior or exterior ornamental lighting control. It is necessary in providing automatic control for the light intensity of elaborate flood-lighting installations to provide some means for producing a record, one for each circuit, which can be laid out in advance and then utilized in conjunction with the control apparatus to control the light intensity in 10 accordance with a predetermined program.

An object of my invention, generally stated, is to provide apparatus for controlling the current in a plurality of electrical circuits which shall be simple and efficient in operation and which 20 may be readily and economically manufactured and installed.

A more specific object of my invention is to provide for controlling the current in a plurality of electric circuits in accordance with a predetermined program.

25 A further object of my invention is to provide a current-controlling system in which the program of control may be readily changed as desired.

30 Other objects of my invention will be described fully hereinafter or will be apparent to those skilled in the art.

As one embodiment of my invention, an alternating-current lighting circuit is controlled by 35 means of a magnetic amplifier such as a reactor having a direct-current control winding. The control winding of the reactor is energized through an amplifying circuit comprising a plurality of thermionic tubes. The grid-biasing potential applied to the control tube of the amplifying circuit is regulated by a potentiometer over which a roll of paper, or other non-conducting material, having a conducting track disposed thereon is passed. The potential impressed on 40 the conducting track by the potentiometer is determined by the portion of the potentiometer with which the track is in contact which, in turn, is determined by the location of the track on the roll as it is passed over the potentiometer. The 45 track may be so laid out on the roll that the biasing potential applied to the tube unit will be varied as desired, thereby providing a flexible and easily constructed means of controlling the current in a lighting or any other electrical circuit 50 in accordance with a predetermined program.

For a fuller understanding of the nature and scope of my invention, reference may be had to the following detailed description, taken in conjunction with the accompanying drawings, in which:

5 Figure 1 is a view, in elevation, of one unit of an embodiment of my invention;

Fig. 2 is a view, partially in elevation and partially in section, taken along the line II—II of Fig. 1;

10 Fig. 3 is a schematic diagram, illustrating the connections of a lighting control circuit which may be controlled by my invention;

Fig. 4 is a top plan view of a modification of 15 my invention, and

Fig. 5 is a view, in elevation of the embodiment of the invention shown in Fig. 4.

Referring to the drawings, and particularly to Figs. 1 and 2, which show one of a plurality of units which may be utilized for controlling a plurality of electrical circuits, a potentiometer 10 is wound upon a roller which is mounted upon a supporting panel 11. As shown, contact fingers 12 are disposed to engage contact rings 13 on the ends of the roller thereby providing means of connecting the terminals of the potentiometer to a battery or other suitable source of direct-current energy.

20 In the embodiment of the invention illustrated in Figs. 1 and 2 a conducting track 14, composed of copper braid, is secured to a celluloid ribbon 15 which may be wound from a spool 16 onto a similar spool 17. It will be understood that the ribbon 15 may be composed of paper or other suitable material, also that the track 14 may be drawn 25 on the ribbon with a suitable conducting material, such as india ink or the like.

20 The spool 17 and the film or ribbon 15 are driven by a mechanical drive similar to that utilized on motion picture machines and comprising a motor 18 which drives a sprocket wheel 19 through a shaft 20 and a worm gear 21. The spool 17 is driven by a spring belt 22, thereby providing the necessary flexibility to keep from breaking the film 15. A spring-biased pressure 40 roller 23 is provided in order to maintain the braid 14 in contact with the potentiometer winding 10. A pick-up roller 24 and a brush 25, which engages the roller 24, are provided to receive the voltage from the conducting track 14 for connection to the thermionic tube control unit. If desired, instead of providing the pick-up roller 24, the end of the conducting track 14 may be connected to the shaft of the spool 17 and the potential taken from the shaft by means of a brush, 50 55

similar to the brush 25, which engages the shaft on which the spool 17 is mounted.

It is evident that as the film 15 and the conducting track 14 pass over the potentiometer 10 the potential impressed on the conducting track will vary as its location on the film varies. That is, if the track 14 is so located on the film that it is travelling under one end of the potentiometer a low voltage will be impressed on the track and if the track is travelling under the other end of the potentiometer, a high voltage will be impressed on the track. Similarly, when the track makes contact with intermediate points on the potentiometer, a corresponding voltage is impressed thereon.

As previously stated, the pick-up roller 24 is disposed to engage the track 14 shortly after it leaves the potentiometer 10 so that the voltage on the pick-up roller is determined by the position of the track 14 under the potentiometer 10. By means of the brush 25, which engages the roller 24, and a conductor 26 the varying potential of the track 14 may be impressed on a thermionic-tube amplifying unit and thereby utilized 25 to control the current in an electric circuit such as a theatre lighting circuit or an ornamental flood-lighting circuit.

It is apparent that the track 14 may be previously so laid out on the film 15 that the desired 30 intensity of illumination will be secured at any time during the progress of the film under the potentiometer, also that the location of the track on the film may be easily altered in order to vary the lighting effects secured. In this manner 35 a flexible and easily constructed means for laying out a program for controlling the current in an electric circuit is provided. If it is desired to control a plurality of circuits, additional units similar to the one shown may be provided, a roll 40 of film having a conducting track being provided for each circuit. The rolls may be mounted on additional panels and driven by the shaft 20 and worm gears in a manner similar to that shown. Since all of the rolls are driven by a common shaft, they operate at the same speed, thereby 45 keeping the programs of the various circuits in synchronism.

A thermionic tube amplifying circuit of the type illustrated in Fig. 3, and which is fully described in Patent No. 1,966,222, issued July 10, 50 1934, to R. D. Ross, and assigned to the Westinghouse Electric and Manufacturing Company may be utilized in conjunction with the apparatus herein described to control the current in a lighting circuit. However, it will be understood that 55 amplifying circuits of various other types, well known in the art, may be readily utilized in conjunction with my invention.

Referring to Fig. 3, a lighting circuit 30 is 60 illustrated as having lamps 31 supplied with alternating current through conductors 32 which may be energized from any suitable source of alternating current. The current flowing through the lamps 31 is controlled by a three-legged reactor 33 in a manner described in the copending application of R. D. Ross. The reactor 33 is 65 provided with alternating-current windings 34 and 35 and a direct-current control winding 36. The normal inductance of the windings 34 and 35 70 is such that the lamps 31 will not be lighted, however, by energizing the control winding 36 with direct current the iron core of the reactor is saturated to a degree depending upon the current flowing in the winding 36, thereby reducing the 75 impedance of the windings 34 and 35 and permit-

ting the lamps 31 to be lighted. In this manner the intensity of the illumination supplied by the lamps 31 may be controlled by varying the amount of direct current flowing in the control winding 36.

As shown, the control winding 36 may be energized by means of a direct-current generator 37 or other suitable source of power through the plate circuits of two tubes 38 and 39 which are connected in parallel-circuit relation. The plate current of these tubes may be regulated by means of a control tube 41 in cooperation with a direct-current generator 42 or other suitable source and resistors 43 and 44, as described in the aforementioned copending application of R. D. Ross. 15 A varying grid-biasing potential is impressed on the grid of the tube 41 by means of the potentiometer 10 and the conducting track hereinbefore described. In this manner the current flowing in the lighting circuit 30, and hence the intensity 20 of illumination supplied by the lamps 31, may be controlled in accordance with a predetermined program by merely running the film 15 through the control apparatus. As previously stated, the intensity of illumination secured at any time during the program may be varied by changing the location of the track 14 on the film 15, and additional units may be provided for controlling a plurality of circuits.

In the embodiment of the invention illustrated 30 in Figs. 4 and 5 a plurality of conducting tracks 14 are disposed on a revolving disc 50 instead of the film 15. The disc 50 is driven by a motor 18 through a gear reduction 51. The disc may be composed of "Micarta", or any other suitable 35 insulating material and the tracks 14 may be laid out with a conducting ink or they may consist of copper braid or the like secured to the disc in any suitable manner.

As shown, two continuous tracks 14 are laid 40 out on the top side of the disc 50 and two on the bottom side, thereby providing a means of controlling four electric circuits similar to the lighting circuit illustrated in Fig. 3.

Potentiometer windings 10 are wound upon 45 rollers which are mounted above and below the revolving disc 50 in a manner to permit each of the conducting tracks 14 to make contact with one of the potentiometers 10. The tracks 14 may be so laid out on the disc 50 that a varying voltage 50 will be impressed on them as the disc revolves, thereby controlling the intensity of the illumination supplied by each of the lighting circuits in accordance with a predetermined program.

Since the tracks are continuous the program 55 for each circuit is repeated with each revolution of the disc 50. Pick-up rollers 24 are mounted above and below the disc 50 in a manner similar to the potentiometers 10 to engage the tracks 14 in order that the voltage impressed on each of 60 the tracks may be transmitted to the control circuits. Each of the pick-up rollers is provided with a collecting brush 25 which may be connected to the grid of a thermionic tube, thereby providing a means of controlling the current in an electric 65 circuit, as previously described.

It will be understood that provision may be made for controlling any desired number of circuits by increasing the number of tracks on each disc and also by providing additional units similar 70 to the one illustrated.

The program of control may be varied by changing the lay-out of the tracks 14 on the disc and entirely new programs may be provided by placing new discs, having different track lay- 75

outs, in the control apparatus. The frames which support the potentiometer and the pick-up rollers are hinged at 52 in order that the disc 50 may be readily removed and a different one 5 inserted in its place.

As previously stated, the invention herein described is not limited to the control of lighting systems, but it may be readily utilized in various other electrical control systems, as, for example, 10 load-dispatching systems, wherein it is desired to regulate the load on a particular circuit or system, in accordance with a predetermined schedule.

It may also be utilized to control the operation of electrically controlled valves, conveyors and 15 other apparatus, the operation of which may be controlled in accordance with a predetermined program.

Since numerous changes may be made in the above-described construction, and different embodiments of the invention may be made without departing from the spirit and scope thereof, it is intended that all matter contained in the above 20 description or shown in the accompanying drawings shall be interpreted as illustrative and not 25 in a limiting sense.

I claim as my invention:

1. In apparatus for controlling an electrical condition of a circuit, in combination, a rotatable potentiometer winding, means for impressing a 30 substantially constant potential on the potentiometer winding, conducting means disposed on a carrier to engage varying portions of the potentiometer winding to receive a potential which varies in accordance with the position of the conducting means on the carrier, and means for impressing said varying potential on an electric circuit to control an electrical condition thereof.

2. In apparatus for controlling an electrical condition of a circuit, in combination, a potentiometer winding, means for impressing a substantially constant potential on the potentiometer winding, a conducting track disposed to engage the potentiometer winding at predetermined points to receive a potential which varies 40 in accordance with a predetermined program, and means for impressing said varying potential on an electric circuit to control an electrical condition thereof.

3. In apparatus for controlling an electrical 50 condition of a circuit, in combination, a rotatable potentiometer winding, means for impressing a substantially constant potential on the potentiometer winding, a flexible electrical conductor, means for moving the flexible electrical conductor 55 across the potentiometer winding to engage it at predetermined points to receive a potential which varies in accordance with a predetermined program, and means for impressing said varying potential on an electric circuit to control an electrical condition thereof.

4. In apparatus for controlling an electrical condition of a circuit, in combination, a potentiometer winding, means for impressing a substantially constant potential on the potentiometer winding, a track composed of an electrical 65 conducting material, a non-conducting carrier for supporting the track, means for moving the carrier and the track across the potentiometer winding to engage it at predetermined points to 70 receive a potential which varies in accordance with a predetermined program, and means, for impressing said varying potential on an electric circuit to control an electrical condition thereof.

5. In apparatus for controlling an electrical 75 condition of a circuit, in combination, a poten-

tiometer winding, means for impressing a substantially constant potential on the potentiometer winding, a conducting track disposed on a flexible non-conducting carrier in a predetermined layout, means for moving the carrier across the potentiometer winding to cause the track to engage the potentiometer winding at predetermined points in accordance with the layout of said track to receive a varying potential from said potentiometer, and means for impressing said varying 10 potential on an electric circuit to control an electrical condition thereof.

6. In apparatus for controlling an electrical condition of a circuit, in combination, a potentiometer winding, means for impressing a substantially constant potential on the potentiometer winding, a flexible conducting track disposed on a non-conducting carrier in a predetermined layout, means for moving the carrier across the potentiometer to cause the track to engage the 15 potentiometer at predetermined points in accordance with the layout of said track to receive a varying potential from said potentiometer, and conducting means disposed to engage said track to impress said varying potential on an electric 20 circuit to control an electrical condition thereof.

7. In apparatus for controlling an electrical condition of a circuit, in combination, a potentiometer wound upon a rotatable spool, means for impressing a potential on the potentiometer winding, a flexible conductor disposed upon a ribbon of non-conducting material in a predetermined layout, means for drawing the ribbon across the potentiometer to cause the conductor to engage the potentiometer at predetermined points in accordance with the layout of the conductor to receive a varying potential from said potentiometer, and conducting means disposed to engage the flexible conductor to impress said varying potential on an electric circuit to control an electrical 35 condition thereof.

8. In apparatus for controlling an electrical condition of a circuit, in combination, a potentiometer wound upon a rotatable spool, means for impressing a potential on the potentiometer winding, a flexible conductor disposed upon a ribbon of non-conducting material in a predetermined layout, means for drawing the ribbon across the potentiometer to cause the conductor to engage the potentiometer at predetermined points in accordance with the layout of the conductor to receive a varying potential from said potentiometer, a pick-up roller disposed to engage the flexible conductor to receive the varying potential, and means for impressing said potential on an electric 50 circuit to control an electrical condition thereof.

9. In apparatus for controlling an electrical condition of a circuit, in combination, a potentiometer winding, means for impressing a potential on the potentiometer winding, a conductor disposed upon a disc of non-conducting material in a predetermined layout, means for revolving the disc to cause the conductor to engage the potentiometer at predetermined points in accordance with the layout of the conductor to receive a varying potential from the potentiometer, a pick-up roller disposed to engage the conductor to receive the varying potential, and means for impressing said potential on an electric circuit to control an electrical condition thereof.

10. In apparatus for controlling an electrical condition of a plurality of circuits, in combination, a plurality of potentiometer windings, means for impressing a potential on the potentiometer windings, a plurality of conductors disposed upon 75

a disc of non-conducting material in predetermined layouts, means for revolving the disc to cause the conductors to engage the potentiometers at predetermined points in accordance with the layout of the conductors to receive varying potentials from the potentiometers, a plurality of pick-up rollers disposed to engage the conductors to receive the varying potentials, and means for impressing said potentials on electric circuits to control an electrical condition thereof.

11. In apparatus for controlling an electrical condition of a plurality of circuits, in combination, a plurality of potentiometers wound upon rotatable spools, means for impressing a potential 10 on the potentiometer windings, a plurality of con-

ductors disposed upon the top side of a disc of non-conducting material in predetermined layouts, a plurality of similar conductors disposed upon the bottom side of said disc, means for revolving the disc to cause the conductors to engage the potentiometers at predetermined points in accordance with the layout of the conductors to receive varying potentials from the potentiometers, a plurality of pick-up rollers disposed to engage the conductors to receive the varying potentials, and means for impressing said potentials on electric circuits to control an electrical condition thereof. 10

CHARLES P. WEST.
